UNDERWATER SPEAR GUN

Paul M. Arnold, Coral Gables, and Randolph Gordon
Arnold, Miami, Fla.

Application November 29, 1955, Serial No. 39,075

Term of patent 14 years

(Cl. D30—1)

Fig. 1 is a side elevational view of an underwater spear gun showing our new design;

Figure 2 is a bottom plan view thereof;

Figure 3 is a rear view of the barrel as taken along the line 3—3 of Figure 1; and

Figure 4 is a front elevational view.

The broken line portion indicating a spear is for illustrative purposes only.

We claim:

The ornamental design for an underwater spear gun, substantially as shown and described.
